CLAIM

The ornamental design for an interlocking panel, as shown and described.

DESCRIPTION

FIG. 1 is a perspective view looking down one side of the interlocking panel with the other side perspective view being a mirror image; and,

FIG. 2 is a view from one end of the interlocking panel with the other end being a mirror image.

The interlocking panel shown is of indeterminate length.

1 Claim, 1 Drawing Sheet

FIG. 2.

FIG. 1.
